MARRINER A. BROWNING, OF OGDEN, UTAH, ASSIGNOR TO J. M. & M. S. BROWNING COMPANY, OF OGDEN, UTAH, A CORPORATION OF UTAH

TRIGGER MECHANISM

Application filed September 9, 1931. Serial No. 561,850.

This invention relates to improvements in trigger mechanism for double guns (either of the side by side or the over and under types) in which the barrels may be fired in succession upon successive pulls of the trigger, and it has particular reference to trigger mechanism such as disclosed and claimed in the Val A. Browning application Serial Number 534,469, filed May 2, 1931, and assigned to the J. M. & M. S. Browning Company, the owner of the present application.

The aim of the present invention is to provide an improved trigger mechanism of this kind having but one trigger and provided with means whereby the barrels may be fired selectively in either order upon successive pulls of the trigger; that is to say, the over barrel first and then the under one may be fired upon successive pulls, or the order may be reversed.

A further aim of the invention is to provide an improved trigger mechanism which is very simple in construction and effective in operation.

Other objects will be in part obvious, and in part pointed out more in detail hereinafter.

The invention accordingly consists in the features of construction, combination of elements and arrangement of parts which will be exemplified in the construction set forth and the scope of the invention of which will be indicated in the appended claims.

In the accompanying drawing, wherein is shown, for illustrative purposes, one of the embodiments which the present invention may take, it being understood that this disclosure is by way of exemplification only and the improvements may be incorporated in guns of various kinds and types and in connection with firing mechanisms of various styles.

Fig. 1 is a side elevational view of my improved arrangement, with both of the hammers in cocked position and with the trigger unpulled, the connector being in such position that upon the first pull of the trigger the left-hand hammer will be released;

Fig. 2 is a perspective view of certain of

the parts shown in the position which they have in Fig. 1;

Fig. 3 is a similar view showing the connector shifted into operative relation to the right-hand sear;

Fig. 4 is a view similar to Fig. 1, with the left-hand hammer in released position and the single trigger in pulled condition;

Fig. 5 is a perspective view of the connector; and

Fig. 6 is a detail view taken on line 6—6 of Fig. 1.

Referring to the drawing in detail, 10 designates the frame of the gun, the same being shown more or less diagrammatically, as it may be of any suitable construction, the particular form and shape thereof forming no part of the present invention. The firing mechanism includes a pair of hammers 11 and 12 pivoted as at 13. Respectively associated with these hammers are the sears 14 and 15 which may be of any suitable construction. These sears are pivoted on a pin 16. Each of the hammers is normally urged into firing position by respective springs, only one of which is shown, that spring being designated by the numeral 17. Each of the hammers has, on its outer face, a notch 18 adapted to be engaged by a tooth 19 on the respective sear for holding the hammer in cocked position. The sears are normally urged into engagement with the hammers by springs 20 which may be of any suitable form. In the present instance, the rear ends of these sears are provided in their opposed faces with notches 21 and 22 which, in effect, form a rectangular opening. By notching the sears as described, they respectively have, at their extreme rear ends, normally aligned tails or offsets 23 and 24.

In accordance with the present invention, the gun is provided with a single trigger associated, by means of a connector, with the sears. In the present instance, the trigger 25 is located in a slot in the bottom of the frame 10 and is pivoted on a pin 26. It has a recess 27 forming a socket in which the pin 28 on the lower end of the connector 29 seats. The upper end of the connector has a finger 31 projecting through the opening 100

formed by the notches 21 and 22, the width of this finger being less than the width of either of these notches. Rearwardly of and at the lower end of the finger is a shoulder 32 which is adapted to selectively engage beneath the tails 23 and 24 of the sears. The connector has, adjacent its upper end but below the shoulder 32 and on each side, cams which are inclined upwardly and 10 outwardly. The cam on the left-hand side is designated by the numeral 33 and that on the right-hand side by the numeral 34. For the purpose of adjusting the connector laterally in order to permit of selectability as to which barrel will be fired first, as desired, there is provided a shifter 40 mounted for sliding movement in the same slot as that in which the web of the trigger is located. The shifter has a hump 41 20 against which the finger or thumb may be pressed when it is desired to move the shifter from one position to another. The forward end of the shifter may have a notch 42 for accommodating the pin 26 and the rear end of the shifter may be guided by the bottom tang of the frame. The shifter has an upstanding lug 43 of somewhat wedge shape in horizontal cross section, thus providing oppositely disposed cam faces 44 and 45. 30 The numeral 46 designates a spring which has four functions: First, it normally urges the trigger into unpulled condition; second, it maintains the connector in engagement with the trigger; third, it serves as an operative connection between the shifter and the connector; and, fourth, it resiliently holds the shifter in either its forward or rearward positions. This spring may be formed from a length of spring wire bent generally into 40 U-shape so as to provide a pair of arms which straddle the connector. The connector is secured to these arms as by means of a pin 47. The closed end of the wire is bent upwardly and is provided with an eye 48 which bears 45 against a rear member of the frame, it being secured thereto by a screw 49. The left-hand arm of the wire is provided with a cam 50 in the form of a hump which is supplemental to the cam projection 43 of the shifter. The arrangement is such that when the shifter is in its rearmost position, the high point of the hump 50 engages the cam surface 44 or projection 43 just forwardly of the high point of this projection, so that the arm 50 of the spring is held or urged towards the left, thus holding the connector in the position shown in Fig. 2 and in which position the shoulder 32 of the connector is beneath the offset or tail 23 of the left-hand sear 14. 55 60 When the shifter is moved to its foremost position, the hump engages the inclined or cam surface 45 of the projection 43 at a distance sufficiently remote from the high point of the projection 43 that the spring may assume its normal condition and in which

condition it holds the connector in the position shown in Fig. 3.

The numeral 70 designates a safety latch connected by means of a pin 71 to a thumb piece 72. The safety latch and thumb piece are held to their seats by a spring 73. The upper tang of the frame has two notches 74 and 75 in which a lug 76 on the safety latch is adapted to selectively engage. The forward end of the safety latch has a head 77 which, when the safety latch is in "safe" position, is immediately above the finger 31 of the connector, as shown by dotted lines in Fig. 1. When the safety latch is in this position, the trigger cannot be pulled. The safety latch, rearwardly of the head 77, has a wedge shaped portion 78 so arranged that, when the safety is in off position and the trigger is pulled, the safety will not interfere with the lifting movement of the connector. This wedge shaped portion forms a partition which prevents accidental shifting of the connector from one sear to the other while the trigger is held in pulled position. In Fig. 4, the trigger is shown as having been pulled to release the left-hand hammer, and it will be seen that, while the trigger is held in pulled position, the upper end of the finger 31 lies alongside of the left-hand side of the portion 78 of the latch. It is seen that the wedge shaped portion 78 is truncated so as to provide on its underside a downwardly facing surface disposed between the side walls of the portion 78. This surface is disposed above the opposed faces of the sears 14 and 15 and serves to prevent pulling of the trigger and firing of the gun while the connector is in an intermediate position.

Pivoted as at 54 to the rear tang piece of the frame is a pair of intermediate members or changing levers designated by the numeral 51, these levers being of the same construction and arrangement as those shown in the said Val A. Browning application. Each lever is normally urged upwardly and forwardly by a respective spring 52 of any suitable type. Each of the levers has a forwardly extending finger 53, and these fingers straddle the connector. The levers also have downwardly and inwardly curved arms or portions 55 adapted to cooperate with the inertia member which will now be described, this arrangement being generally similar to that disclosed in said Val A. Browning application. The inertia member may be in the form of a cylinder 60 having a stem 61, the cylinder being mounted for sliding movement in a tube 62. Behind the cylinder is a spring 63 normally urging the inertia member to its foremost position.

In describing the operation of my improved trigger mechanism, it may be assumed that it is incorporated in a gun of the over and under type and that the over barrel is

associated with the left-hand barrel and the under one with the right-hand one. When the hammers are cocked, they move and hold the changing levers in the position shown in Fig. 1. If it is desired to fire the over barrel first and then the under one, the shifter is moved to the rearmost position shown in Figs. 1 and 2 so that the projection 43 of the shifter engages the high point of the hump 5 or cam 50 of the spring 46 whereby this spring, being thus flexed towards the left, will pull and hold the connector in a position where the projection or finger 31 thereof engages in the notch 21 of the left-hand sear, 10 the shoulder 32 being beneath the tail 23 of that sear. When the trigger is pulled the first time, that is, raised from the position shown in Fig. 1 to that shown in Fig. 4, the connector raises the left-hand sear 14 thereby 15 releasing the hammer 11. The over barrel is thus fired and the gun recoils backwardly, but this movement does not affect the position of the inertia element relative to the trigger mechanism until the rearward movement of the gun is checked by the resistance 20 offered by the shooter's shoulder, whereupon the mass 60 will move rearwardly in the tube 62, and, when the forward end of the stem 61 has been withdrawn rearwardly to a slight 25 extent, the portion 55 of the left-hand changing lever is released therefrom. The spring 52, which is behind that changing lever, will move the changing lever to the position shown in Fig. 4 and in which position the 30 finger 53 engages the lower end of the inclined cam 33. The spring 52 is too weak to cause the lever to ride up this cam. The rear edge of the portion 55 of the changing lever is now in the path of movement of the stem 61 35 of the inertia element. After the gun has completed its recoil movement, it rebounds forwardly, and the mass 60 lags behind the forward jump of the gun, and, during this time, the connector is held in engagement with the 40 left-hand sear by the spring 46 so that, if the trigger should be pulled again, the other sear will not be released; that is, there can be no "doubling". After the gun has completed its forward rebound movement, the spring 45 behind the inertia element forces that element forwardly and, due to the engagement of the stem 61 against the portion 55 of the changing lever, the latter will move from the position shown in Fig. 4 to a higher position. 50 When the lever is thus moved, it rides up the cam 33 so that the connector is rocked to the right and into the position shown in Fig. 3, after the trigger is released. The shoulder 32 is now in proper relation to the right-hand sear. When the trigger is again pulled, 55 the right-hand sear is raised so as to release the right-hand hammer to fire the under barrel. If it is desired to fire the under barrel first and then the over one, the shifter is moved to its foremost position shown in Fig. 65

3 and, in which position, the projection 43 is in advance of the hump or cam 50 of the spring 46. The spring 46, now being free to assume its normal position, will rock the connector to its right-hand position and, in which position, the shoulder 32 is in operative relation to the right-hand sear 15. When the trigger is pulled, the under barrel will be fired, and the operation will be generally similar to that just described, except that the right-hand changing lever will cooperate with the cam 34 to shift the connector into operative relation to the left-hand sear. 70

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense. 80

It is also to be understood that the language used in the following claims is intended to cover all of the generic and specific features of the invention herein described and all statements of the scope of the invention which, as a matter of language, might be said to fall therebetween. 90

I claim as my invention: 95

1. In combination, a pair of hammers, a sear for each hammer, a single trigger, a connector through which said sears are successively operated upon successive pulls of the trigger, said connector being adjustably supported whereby the same may be selectively set so that the sears will be operated in the desired order on repeated pulls of the trigger, means for selectively setting said connector, an inertia element having a relative rearward movement upon the rebound of the gun, a spring normally urging said inertia element forwardly, and means interposed between said inertia element and connector whereby said spring moves said connector from the fired to the unfired sear upon return of the inertia element to initial position. 100
2. In combination, a pair of hammers, a sear for each hammer, a single trigger, a connector operated thereby and arranged to move from operative relation to one sear into operative relation with the other sear after the first barrel has been fired and the trigger is released, said connector being adjustably supported whereby the same may be selectively set so that the sears will be operated in the desired order upon repeated pulls of the trigger, means for selectively setting said connector, an inertia element adapted to lag behind the forward rebound of the gun and normally urged into forward initial position, and a pair of intermediate members interposed between said inertia element and connector. 115
3. In combination, a pair of hammers, a 120

sear for each hammer, a single trigger, a connector supported by said trigger and arranged to successively actuate said sears on repeated pulls of the trigger, said connector being supported for selective adjustment relative to the sears, means for selectively setting said connector, an inertia element adapted to lag behind the forward rebound of the gun and normally urged forwardly, and a pair of intermediate members interposed between said connector and inertia element, said connector having portions adapted to be respectively engaged by said intermediate members, each of said intermediate members having a portion normally out of the path of the inertia element and adapted to be automatically brought into said path of movement during the forward rebound of the gun.

4. In combination, a pair of hammers, a sear for each hammer, a single trigger, a connector carried thereby and adapted to be automatically shifted from engagement with one sear into engagement with the other sear only in the event the gun is fired upon the first pull of the trigger, said connector being supported for selective adjustment relative to said sears, means for selectively setting said connector, an inertia element adapted to lag behind the gun on the forward rebound thereof, a spring normally urging said inertia element forwardly, a pair of changing levers, and portions on the opposite sides of said connector adapted to be respectively engaged by said changing levers.

5. In combination, a pair of hammers, a sear for each hammer, a single trigger, a connector carried thereby and adapted to shift laterally from engagement with one sear into engagement with the other sear when the gun is fired upon the first pull of the trigger, said connector being adjustably supported whereby the same may be selectively set so that the sears will be operated in the desired order, means for selectively setting said connector, said connector having a cam on each side face, an inertia element, and a pair of intermediate members respectively associated with said cams whereby, in one selective setting of the connector, said inertia element will cause one of said intermediate members to engage one of said cams to shift the connector after one of the barrels is first fired and, in the other selective setting of the connector, said inertia element will cause the other intermediate member to shift the connector when the other barrel is first fired.

6. In combination, a pair of hammers, a sear for each hammer, a single trigger, a connector carried thereby and adapted to shift laterally from engagement with one sear into engagement with the other sear when the gun is fired upon the first pull of the trigger, said connector being adjustably supported whereby the same may be selectively set so

that the sears will be operated in the desired order, means for selectively setting said connector, said connector having a cam on each side face, an inertia element, and a pair of intermediate members respectively associated with said cams whereby, in one selective setting of the connector, said inertia element will cause one of said intermediate members to engage one of said cams to shift the connector after one of the barrels is first fired and, in the other selective setting of the connector, said inertia element will cause the other intermediate member to shift the connector when the other barrel is first fired, each of said intermediate members being maintained by said inertia element in a position in which it has no influence on the connector while said inertia element is in its initial position, that intermediate member which will act upon the connector in its selective position being released from said inertia element when the latter lags behind the gun, said inertia element, when returning to initial position, causing said intermediate member to act upon said connector to shift the same.

7. In combination, a pair of hammers, a sear for each hammer, a single trigger, a connector supported by said trigger and arranged to selectively engage said sears on repeated pulls of the trigger, said connector being adjustably supported whereby the same may be selectively set so that the sears will be operated in the desired order, means for selectively setting said connector, said connector having a cam on each of its side faces, a first changing lever adapted to cooperate with one of said cams in one setting of the connector, a second changing lever adapted to cooperate with the other cam of said connector in the other setting of the latter, and an inertia element for controlling the movement of said changing levers.

8. In combination, a pair of hammers, a sear for each hammer, a single trigger, a connector carried thereby and adapted to shift from one sear to another when the first barrel is fired, said connector being supported for selective adjustment relative to the sears, means for selectively setting said connector, said connector having a cam on each of its side faces, and a pair of changing levers straddling said connector, one of said cams being in the path of movement of one of said changing levers in one setting of the connector and the other of said cams being in the path of movement of the other changing lever in the other setting of the connector, an inertia element adapted to lag behind the forward rebound of the gun, and a spring normally urging said inertia element forwardly, each of said changing levers having a portion normally out of the path of movement of said inertia element and movable thereinto upon relative rearward movement of said inertia element.

9. In combination, a pair of hammers, sears respectively associated therewith, a trigger, a connector through which said sears are successively operated upon successive pulls of the trigger, an inertia element having a relative rearward movement upon rebound of the gun, a spring normally urging said inertia element forwardly, means between said inertia element and connector whereby said spring moves said connector from the fired to the unfired sear upon return of the inertia element to its initial position, and means for preventing shifting of the connector from one position to another while the trigger is in pulled condition. 10. In combination, a pair of hammers, a sear for each hammer, a single trigger, a connector supported by said trigger and arranged to successively actuate said sears on repeated pulls of the trigger, said connector being supported for selective adjustment relative to the sears, means for selectively setting said connector, a safety latch adapted in one position to lie above said connector to prevent actuation thereof, said safety latch also having a portion to the side of which said connector extends when the trigger is pulled, an inertia element, and a pair of intermediate members interposed between said connector and inertia element. 11. In combination, a pair of hammers, sears respectively associated therewith, a trigger, a connector carried by said trigger and arranged to successively actuate said sears on repeated pulls of the trigger, said connector being supported for selective adjustment relative to the sears, a slidable shifter for selectively setting said connector, and a spring normally urging said connector to its seat on said trigger and constituting a connection between said connector and shifter. 12. In combination, a pair of hammers, sears respectively associated therewith, a trigger, a connector carried by said trigger and arranged to successively actuate said sears on repeated pulls of the trigger, said connector being supported for selective adjustment relative to the sears, a slidable shifter for selectively setting said connector, and a spring normally urging said connector to its seat and said trigger to unpulled position, said spring having a hump adapted to cooperate with said shifter. 13. In combination, a pair of hammers, sears respectively associated therewith, a trigger, a connector carried by said trigger and arranged to successively actuate said sears on repeated pulls of the trigger, said connector being supported for selective adjustment relative to the sears, a slidable shifter for selectively setting said connector, and a spring urging said connector and trigger to normal position, said spring having a hump and said shifter having a projection cooper- 70 75 80 85 90 95 100 105 110 115 120 125
